5 Claims. (Cl. 103—87)

The present invention is related to a pump unit having an impeller driven by an electric motor and in particular to a pump unit usable as a submersible sinking pump, bore hole pump or bilge pump. For such a pump unit it is essential that it can work at a very small liquid depth and that the pump unit has a diameter as small as possible.

It is known in the art to provide a pump unit for this purpose with a substantially cylindrical pump housing which is provided with an inlet opening at the one end and an outlet opening at the other end and in which an electric motor with an impeller attached to one end of the motor shaft is disposed coaxially to the symmetry axis of the pump housing so that an annular space of substantially uniform breadth is formed between the motor and the pump housing, said space forming a duct from the inlet opening to the outlet opening of the housing for the liquid being pumped. In such a pump the impeller is normally attached to the end of the shaft of the electric motor which is adjacent to the inlet opening of the pump housing so that the pump unit can work at a very small liquid depth. This construction of the pump unit has the advantage that the maximum diameter of the pump unit may be kept small. The maximum diameter is in this case in principle determined by the diameter of the motor and the breadth of the annular duct around the motor for the liquid being pumped. In order to avoid that the width of the pump unit at any point exceeds this smallest necessary diameter, the outlet opening from the pump housing and the devices for connecting a pressure pipe or hose to the pump must, however, be disposed at the one end surface of the pump housing and entirely within the circumference of the pump housing determined by said smallest necessary diameter. As however the diameter of the outlet opening and of the pressure conduit connected to the pump unit must be considerably larger than the breadth of the annular duct on the outside of the motor, it will be necessary that the outlet opening and the connecting means for the pressure conduit are located partly or entirely above the end surface of the motor which is opposite to the impeller. This involves, however, the substantial disadvantage that the motor will not be accessible for inspection or repair or replacement, without the pressure conduit connected to the pump unit as well as the end plate of the pump housing comprising the outlet opening being previously dismounted. Further it will not be possible to use an electric motor of standard type, as the end shield of the motor opposite to the impeller should preferably be so designed that it also comprises the outlet opening of the pump unit and the coupling means for the connection of a pressure conduit or hose to the pump unit.

The object of the present invention is to provide an improved pump unit of the type described above, which does not suffer from the abovementioned disadvantages. With this object in view the electric motor with the impeller attached to one end of the motor shaft in a pump unit of the type referred to is according to the invention so disposed within the pump housing that the symmetry axis of the motor forms an acute angle with the symmetry axis of the pump housing and that the end of the motor adjacent to the impeller is located substantially concentric in the housing so that an annular space having a substantially uniform breadth is formed between this end of the motor and the housing, whereas the opposite end of the motor is located eccentric in the housing so that be-

2

tween this end of the motor and the housing a space is formed having substantially the same form as the surface area between two eccentric circles one of them enclosing the other, the outlet opening from the housing being located at this last-mentioned space.

5 In a preferred embodiment of the invention the end of the motor disposed eccentrically in the housing is so located that its circumference is substantially tangential to the inner wall of the pump housing in one point, whereby the space formed between this end of the motor and the housing will have substantially the form of a moon's sickle. With the motor disposed within the pump housing in the manner according to the invention it becomes possible to arrange the outlet opening of the housing in such a way that it is located entirely within the circumscription of the space between the pump housing and the end of the motor located eccentrically within the housing.

In a pump unit according to the invention the maximum diameter of the pump unit is consequently, just as in pump units of the type previously known, determined by the diameter of the motor and the breadth of the space around the end of the motor adjacent to the impeller necessary for the liquid being pumped, due to which the maximum diameter of the pump unit will be as small as possible. 10 In spite of this the end of the motor opposite to the impeller will, due to the fact that the motor is disposed in the pump housing in the manner according to the invention, be easily accessible from the outside of the pump unit, as this end of the motor is not to any part covered by the outlet opening from the pump unit or by the pressure conduit or hose connected to the pump unit. In a pump unit according to the invention it is consequently possible to inspect the motor or remove it from the pump housing e.g. for replacement of the motor or inspection 15 of the interior of the pump housing, without any other parts of the pump unit having to be previously dismounted. Further according to the invention the electric supply conductors and the connection terminal board for the electric motor may be arranged at the end of the motor opposite to the impeller and entirely within the circumference of the motor. The motor can consequently form a separate unit independent of and removable from the remaining part of the pump unit, due to which a motor of standard type can be used.

20 40 45 In the following the invention will be further described with reference to the enclosed drawing, wherein

FIGURE 1 is a sectional view of a pump unit according to the invention;

FIGURE 2 is a sectional view taken along line II—II in FIG. 1; and

FIGURE 3 is a section taken along line III—III in FIG. 1.

For the sake of simplicity no details within the motor casing of the pump unit are shown in FIGS. 2 and 3.

55 The pump unit shown in the drawing comprises a cylindrical pump housing 1 having an outlet opening 2 at its upper end and a connection element 3 for a pressure pipe or hose. At its lower end the pump housing 1 is provided with an inlet opening 4 and a suction basket 5. The 60 peripheral wall of the suction basket is provided with openings 6, through which the liquid being pumped by the pump unit flows into the pump. The pump unit can consequently operate when standing on its lower end surface in the manner normally used for submersible sinking pumps or bilge pumps. The pump unit comprises also an electric motor 7 with a cylindrical motor casing 13, a stator core 14 with a stator winding 15, a rotor 16 and a rotor shaft 17. The rotor shaft 17 projects through one of the end surfaces of the motor casing 13 and an impeller 8 is attached to the end of the rotor shaft 17. The 65 motor 7 is disposed substantially completely within the pump casing 1 in such a way that a fluid passage 18 lead-

ing from the inlet opening 4 to the outlet opening of the pump casing is formed between the outer cylindrical surface of the motor casing 13 and the inner cylindrical surface of the pump casing 1. According to the invention, the motor 7 is disposed within the pump casing 1 in such a way that the axis of symmetry of the motor casing 13 forms an acute angle with the axis of symmetry of the pump casing 1 with the end of the pump casing 13, adjacent the impeller 8, lying substantially centrally within the pump casing. The opposite end of the motor casing 13 lies eccentrically within the pump casing 1 and is tangent to the inner cylindrical surface of the pump casing 1. In this way the fluid passage 18 will at the lower end of the motor casing 13 near the impeller 8 have an annular cross-section with a substantially uniform breadth, as illustrated in FIG. 2, whereas at the upper end of the motor casing near to the outlet opening 2, the passage 18 will have a crescent-shape cross-section as illustrated in FIG. 3. As a result of this arrangement of the motor within the pump casing, the outlet opening 2 from the pump casing can be disposed entirely within the circumscription of the cross-section of the passage 18 at this end of the pump casing. Consequently, it is not necessary to increase the overall diameter of the pump casing at this outlet end and the upper end surface of the motor 7 will not to any part be covered by the outlet opening of the pump housing or by the connection means for coupling a pressure conduit or hose to the pump unit, but will be immediately accessible from the outside of the pump unit, without any part of the pump unit having to be dismounted. In a pump unit according to the invention it is further possible to dispose the electric supply conductors 10 for the motor 7 and a connection terminal board 11 at the upper end surface of the motor and entirely within the circumference of the motor. By removing only the upper end shield 12 of the motor the motor can be readily inspected without any other parts of the pump unit having to be dismounted. Due to this the maintenance of the pump unit is considerably facilitated, since it is principally the motor of the pump unit which requires maintenance or replacement. Since in the pump unit according to the invention, the motor 7 may form a separate unit independent of any other parts of the pump unit, a motor of standard type can be used.

The invention is, however, of course not limited to exactly the pump shown in the enclosed drawing. Thus, the invention is applicable not only to submersible sinking pumps or bilge pumps or the like but also to normal pump units forming a part of a permanent system of liquid conduits. Also this embodiment of the invention has the pronounced advantage that the driving electric motor of the pump unit can be easily and swiftly dismounted from the pump unit, e.g. for repair or replacement, without any other parts of the pump unit or any part of the permanent conduit network connected to the pump unit having to be dismounted.

What I claim is:

1. A pump unit comprising a substantially cylindrical pump casing having an inlet at one end and an outlet at an opposite end, an electric motor with a substantially cylindrical motor casing having a first end and a second end and a rotatable shaft driven by said motor projecting from said motor casing through said first end thereof, an impeller attached to said projecting shaft, said motor with said motor casing being disposed within said pump casing with said first end of said motor casing and said impeller attached to said shaft projecting through said first end facing the inlet end of said pump casing, said pump casing and the motor casing defining therebetween a fluid passage which leads from said inlet to said outlet, said motor casing being disposed within said pump casing with the axis of symmetry of the motor casing extending at an acute angle relative to the axis of symmetry of said pump casing and with said first end of said motor casing lying substantially centrally within said pump casing and said second end of said motor casing lying eccentrically within said pump casing such that at said first end of said motor casing said fluid passage has an annular cross-section with a substantially uniform breadth and at said second end of said motor casing said fluid passage has a cross-section of varying breadth, said outlet of said pump casing being located at the latter cross-section of said passage.

2. A pump unit as claimed in claim 1, wherein said second end of said motor casing is tangent to said pump casing whereby at said second end of said motor casing said fluid passage has a crescent-shape cross-section.

3. A pump unit as claimed in claim 2, wherein said outlet opening of said pump casing is disposed entirely within the circumscription of the cross-section of said fluid passage at said second end of said motor casing.

4. A pump unit as claimed in claim 1, comprising electrical supply conductor means and electrical terminal means for said motor, said supply conductor means and terminal means being mounted on said motor casing at said second end thereof entirely within the enclosure of said second end of said motor casing.

5. A pump unit as claimed in claim 1, wherein said second end of said motor casing projects beyond said outlet end of said pump casing.
